tion of Delaware

Application July 19, 1937, Serial No. 154,377

16 Claims. (Cl. 178—32)

This invention relates to printing telegraph systems and apparatus and more particularly to two channel systems of telegraphic transmission for controlling telegraphic recorders, and to recorders operative on such a system.

5 An object of the invention is the provision of a relatively simple telegraph system by utilizing two transmission channels for character selection and printing.

10 Another object of the invention is to effect character selection in a printing telegraph receiver, in variable steps, in accordance with the variable number of impulses applied to the signal channel.

15 In accordance with one embodiment of the present invention, the printing apparatus operates on a two channel or wire system in which one line wire is connected through one ratchet-controlled magnet to a winding of a printing magnet, and the other line wire is connected through a second ratchet-controlling magnet to the same winding of the printing magnet. Since the printing magnet is marginal in operation, it responds only to current applied simultaneously 20 on both line wires, and character printing is effected only when both windings of the ratchet-controlling magnets and the winding of the printing magnet are energized. Each character signal consists of three parts; namely, a plurality 25 of stepping impulses, a prolonged printing impulse, and a plurality of restoration impulses, all of which occur concurrently on both line wires. For example, the stepping impulses occurring on one line wire control the stepping of a type wheel 30 one thirty-sixth of a revolution per impulse, and the stepping impulses occurring on the second line wire control the stepping of the type wheel one-sixth of a revolution per impulse. Although these positioning impulses exist on both line 35 wires concurrently or exist during the same signal period but not simultaneously, the impulses on one line wire are staggered with respect to the impulses on the other line, so as not to energize the print magnet prematurely. The maximum number of impulses on either line necessary 40 to step the type wheel from its zero or starting position to the last one of its thirty-six positions is five. The second part of the character signal consists of a prolonged impulse occurring on both lines simultaneously and functions 45 to operate the printing magnet which is designed to operate in response to greater current than the selecting or ratchet-controlling magnets, hence the requirement that the current on both lines simultaneously be necessary to oper-

ate the printing magnet. The third part of the signal consists of a series of impulses, occurring on both line wires concurrently, six on each wire, and staggered similarly to the positioning impulses, so as to affect only the ratchet-controlling 5 magnets and not the printing magnet, the function of which is to effect the restoration of the type wheel to its initial or starting position. Thus, responsive to the restoration impulses is a restoration mechanism which prevents said impulses from rotating the type wheel further than to its zero or starting position.

One modified form of the present invention consists in substituting for the neutral selecting or ratchet-controlling magnets, rotary-armature types of magnet, and arranging the axes of the armatures of the two character selecting magnets in coaxial alignment with the center of the type wheel. The magnets are then adapted to control through differential or planetary gear- 15 ing the selective position of the type wheel. In this form of the invention the printing function is likewise performed by means of a rotary-armature type magnet. A particular feature of this type of printer is the association with each 20 rotary-armature of a multi-toothed cam, with teeth corresponding in number to the pairs of diametrically opposed armature poles, the feature residing in the fact that the armature is rotated in part by the magnet and in part by 25 the spring actuated detent cooperating with the multi-toothed cam, the action of each to effect rotation of the armature occurring alternatively.

The above and other objects of the invention 30 will be apparent from the following description 35 when taken in conjunction with the accompanying drawings, wherein like reference characters designate similar parts throughout the several views, in which,

Having reference to Figs. 1 to 4, the framework of the printing apparatus according to the preferred form of the present invention comprises a base plate 11 supporting a mounting plate 12 attached thereto through the instrumentality of a bar 13 by means of screws 14. A U-shaped bracket 15 is fixed to the mounting plate 12, and together with the mounting plate 12 provides a journal bearing for a type wheel shaft 16, as seen in Fig. 3. Fixed to shaft 16, to the right of mounting plate 12, as viewed in Fig. 3, is a type wheel 17 which has associated therewith a star wheel 18. Between the web of bracket 15 and mounting plate 12, shaft 16 carries thereon a sleeve 19 and a pinion gear 21, the latter pinion being fixed to the shaft 16. Integral with sleeve 19 is a ratchet wheel 22 in which is journaled a shaft 23 which carries fixed thereon, planetary gears 24 and 25 disposed one on each side of the ratchet wheel 22. The planetary gear 25 meshes with the pinion 21, and planetary gear 24 meshes with a pinion 26 which is integral with a sleeve 27 loosely mounted on the sleeve 19. A ratchet wheel 28 is also integral with the sleeve 27. Fixed to shaft 16 to the left of mounting bracket 15 (as viewed in Fig. 3) is a collar 29 which carries a spring post 31 (as viewed in Fig. 2) to which is connected one end of a coiled spring 32, the other end of which is connected to a pin 33 carried on a blocking segment 34 loosely mounted on shaft 16, the function of which will hereinafter appear.

As viewed in Fig. 2, ratchet wheel 22 has associated therewith a pawl 35 carried at the extremity of a pawl operating lever 36 which is associated with an armature 37 of an electromagnet 38. Electromagnet 38 is carried on a bracket 39 which in turn is mounted on a bracket 41 secured to the mounting plate 12. The armature 37 is pivotally supported at 42 to bracket 39 and is biased in a clockwise direction by a spring 43. Spring 43 thus normally, when

magnet 38 is deenergized, maintains pawl operating lever 36 against stop portion 44 of a stop bracket 45.

Ratchet wheel 28 has associated therewith a pawl 46 carried at the extremity of a pawl operating lever 47 which is integral with the armature 48 of an electromagnet 49. Electromagnet 49 is carried on a bracket 51 which is supported on a bracket 52 secured to mounting plate 12. Armature 48 is pivotally supported at 53 on bracket 51 and is biased in counterclockwise direction by a spring 54, which normally maintains pawl operating lever 47 against an adjustable stop 60.

15 A printing magnet 55 is supported through angle brackets 56 and 57 to a plate 58 which in turn is carried by an angle bracket 59 secured to mounting plate 12. In the present embodiment, magnet 55 is provided with two windings, one of which controls an armature 61 pivotally mounted at 62 to the plate 58. Integral with armature 61 is a printing control lever 63 near the extremity of which is secured an extension 64 which acts on a plunger 65 carried in a bracket 66 secured to mounting plate 12. 25 Plunger 65 cooperates with a laterally disposed flange 67 integral with a print hammer 68 (Fig. 1). Flange 67 is formed with a knife-edge to cooperate with the star wheel 18, in well-known manner, to hold the type wheel in printing position during the printing operation. The print hammer 68 is biased to its downward position by a spring 69.

30 The printing magnet 55 is also provided with a second winding which controls an armature 71 pivoted at 72 to plate 58. Armatures 61 and 71 are biased out of engagement with their pole faces by a common spring 73. Armature 71 is provided, integral therewith, with an extension 74 which is so conformed as to avoid the pawl 40 operating arm 47, and which terminates at its extremity in a hook portion 75 which cooperates with a plurality of pins 76 carried on the ratchet wheel 22.

35 Pawl operating lever 47 is provided with a 45 vertically extending arm 77 which terminates at its upper extremity in a laterally directed portion 78. Portion 78 cooperates with the segment 34 during the performance of the restoration function as will presently appear.

40 In Fig. 4 is shown a diagrammatic representation of the type of signals received over the two line wires for effecting the selective control and operation of the printer shown in Figs. 1, 2, and 3. As previously indicated, each character signal consists of three parts; namely, the selecting or stepping impulses 83 and 84 comprising that portion indicated as 79, the prolonged printing impulse comprising that portion indicated 81, and the restoration impulses 85 and 86 comprising 60 that portion indicated 82. In Fig. 4 it may be noted that the selecting impulses 83 received over one line wire are staggered with respect to impulses 84 received over the second line wire, it being understood that the number of impulses 83 or 84 vary with the character received. It will also be observed that the printing impulses 81 impressed on each line wire occur simultaneously and are prolonged in nature. Following the printing impulses are the restoration impulses 85 and 86 which are always, according to the present invention, six in number and are staggered as indicated.

45 Impulses 83 are impressed on electromagnet 38, and as each impulse is received, magnet 38 75

becomes energized and causes its armature 37 to rotate in a counterclockwise direction against the action of spring 43, thus rotating the pawl operating lever 37 counterclockwise to raise pawl 35 to engage the next preceding tooth on the periphery of ratchet 22 preparatory to effecting rotation of said ratchet. Then upon deenergization of magnet 38 at the termination of said impulse, armature 37 and lever 36 are actuated 10 in a clockwise direction by the spring 43 so that pawl 35 rotates the ratchet 22 through one angular step. This movement of ratchet 22 causes the planetary gears 24 and 25 to be carried clockwise and since, during this movement the ratchet 28 is prevented from rotating, the gear 24 will be caused to rotate in a clockwise direction thus imparting the same movement to the companion planetary gear 25. This movement 15 of planetary gear 25 causes pinion 21, and hence type wheel 17 and star wheel 18, to rotate in a counterclockwise direction as viewed in Fig. 2 (or a clockwise direction as viewed in Fig. 1). By properly proportioning the gears involved in this gear chain, the type wheel 17 is moved one 20 angular step representative of a single character space on the periphery of the type wheel for each actuation of pawl 35 by magnet 38.

When a character selecting impulse 84 is received over the second line wire, it causes the 30 energization of magnet 49 which, upon energization, attracts its armature 48 to impart clockwise rotation to the pawl operating lever 47 against the action of its spring 54 sufficiently to permit pawl 46 to engage the next preceding 35 tooth on the ratchet wheel 28. Then, upon termination of said selecting impulse, magnet 49 becomes deenergized and spring 54 acts to rotate armature 48 and lever 47 counterclockwise, thus actuating pawl 46 upwardly to effect the 40 counterclockwise rotation of ratchet wheel 28 one angular step. Since ratchet wheel 22 is at this time held against rotation by its pawl 35, the counterclockwise rotation of ratchet wheel 28 effects, through gear 26 and planetary gears 24 45 and 25 counterclockwise rotation of pinion 21 and type wheel 17, as viewed in Fig. 2. However, instead of rotating the type wheel only one angular step representative of a single character space, type wheel 17 is rotated six angular steps 50 or through the span of six character spaces of the periphery of the type wheel 17.

As previously mentioned, character selecting impulses are received over both line wires concurrently except that the impulses on one wire 55 are staggered with respect to the other, and the number of impulses received over each line wire is determined by the character to be selected. Remembering that the type wheel is restored to an initial or starting position prior to the selection and printing of each character, it will be assumed that the fifth character on the type wheel counting from the initial or starting position is to be selected. In this event, five impulses 83 will be received over the first line wire 60 (and none over the second line wire), thus energizing magnet 38 five times and rotating ratchet 22 through the angular distance of five teeth to effect the rotation of the type wheel 17 correspondingly to present the fifth character 65 on the type wheel (counting from the initial or starting position) to the printing point. Now, in the event that it is desired to print the eleventh character on the type wheel counting from the initial or starting position, five impulses 83 will 70 be received over the first line wire to actuate

magnet 38 and to rotate ratchet 22 five angular steps, and hence type wheel 17 five character spaces; and one selecting impulse 84 will be received over the second line wire to energize magnet 49 to operate lever 47 to effect the rotation 5 of ratchet 28 one angular step, in a manner previously described, to cause the rotation of type wheel 17, in a single movement, six character spaces which, when added to the five character space movement resulting from the operation of magnet 38, will have caused the type wheel to be moved through eleven character spaces, thus presenting the eleventh character (counting from the starting position of the type wheel) to the printing point. It is thus seen that time has 10 been saved in selecting the eleventh character on a type wheel by operating magnet 38 only five times and magnet 49 only once, instead of operating magnet 38 eleven times. Likewise, if magnet 49 is operated twice and magnet 38 is operated five times, the seventeenth character will 15 be presented to the printing point. The latter selection will have been achieved through the transmission of only seven impulses, instead of seventeen impulses, thus emphasizing the decided 20 saving in line time. To select the thirty-fifth or last character on a type wheel (the thirty-sixth or zero position being the blank position of the type wheel), only five impulses 83 need be transmitted to operate magnet 38 five times, and five 25 impulses 84 need only be transmitted to operate the magnet 49 five times. Thus, in all, ten impulses have been transmitted instead of thirty-five.

After the receipt of the character selecting 30 impulses 83 and 84, the selection of the character to be printed from the type wheel has been determined, and following the receipt of these selecting impulses 83 and 84 a prolonged printing 35 impulse 81 is received over both line wires simultaneously, thus energizing the print magnet 55, causing armature 61 thereof to be attracted and printing arm 63 to be actuated in a counterclockwise direction against the action of spring 73 to impart, through portion 64, upward movement to plunger 65, which through lateral portion 67 imparts counterclockwise movement (as viewed in Fig. 1) to printing hammer 68, thus throwing the pallet portion of the printing arm 68 against the type wheel 17. At the same time 40 45 the knife-edge of portion 67 cooperates with the star wheel 18 to prevent movement of the type wheel 17 during the performance of the printing function.

The tape 87 is directed in tape guide 88 through the printing area. Engaging tape 87 through a slot (not shown) in the tape guide 88 is a tape spacing roller 89 which is provided, as is common practice, with a knurled periphery and which, to effect movement of the tape, cooperates with a pressure roller 91 carried on a lever 92 which is spring biased in a counterclockwise direction (as viewed in Fig. 1) by a spring 93. Roller 89 is mounted on a shaft 94 (Fig. 2) to which is also fixed a spacing ratchet 95. Cooperating with spacing ratchet 95 is a pawl 96 which is carried at the extremity of the printing lever 63. Thus, upon each operation of lever 63 in response to the printing impulse 81, the pawl 96 is reciprocated thereby engaging the next 50 tooth on the ratchet 95 and upon a downward movement of pawl 96, ratchet 95 is rotated one angular step in a clockwise direction (as viewed in Fig. 2) thus causing roller 89 to be rotated one angular step in a counterclockwise direction (as 55 60 65 70 75

viewed in Fig. 1). A detent spring 97 is provided to prevent back spacing of the ratchet wheel 95 during the performance of the spacing operation. Associated with the type wheel 17, as viewed in Fig. 1, is an inking roller 98 carried on a lever 99 biased by a spring 100.

As previously indicated, the third part of each character signal comprises a plurality of impulses over each line wire, sufficient in number to insure the stepping of the type wheel forward (in the same direction as for character selection) to its starting or zero position. Since six impulses over each line wire are sufficient to rotate the type wheel a complete revolution, this number of impulses on each line has been chosen to effect restoration. Of course, the extent to which it is necessary to rotate the type wheel to its zero position after the selection of a character varies with the character selected. Therefore, it is necessary to provide mechanism to prevent rotation of the type wheel farther than to its zero position. To achieve this result in connection with the six-step magnet 49, the segment 34 and arm 77 are provided, and in connection with the one-step magnet 38, the pins 76 and arm 74 are provided.

The magnets 38, 49, and 55 are connected in the manner shown in Fig. 16 wherein the magnet 38 is included in one line wire 314 and the magnet 49 is included in the other line wire 315, magnet 55 being connected to both line wires so that impulses received over line wire 314 will pass through magnet 38 thence through magnet 55 to ground. In the form of the invention shown in Fig. 2, the magnet 55 is provided with two windings, one of which is marginal in character (and controls armature 61) so that the impulses received over only one of the line wires will not energize the marginal winding of the magnet. On the other hand, it requires the total current on the two wires to effect the energization of said marginal winding of magnet 55. Magnet 55 is also provided with a second winding which responds to the selecting and restoration impulses over either wire to cause the operation of armature 71.

Now, when the restoration impulses 85 are received over line wire 314, they will pass through magnet 38 and also the second mentioned winding of magnet 55. The effect of restoration impulses 85 on magnet 38 will be to operate arm 36 and pawl 35 to cause the clockwise rotation of ratchet wheel 22. However, since these restoration impulses also pass through the second mentioned winding of magnet 55, armature 71 is operated to rotate lever 74 clockwise to bring hook portion 75 into the path of pins 76. Thus, pawl 35 will continue to actuate ratchet wheel 22, in response to the restoration impulses 85, only until one of the pins 76 is intercepted by the hook portion 75 after which the remaining restoration impulses 85, if any, will have no effect. During the character selecting operation, the actuation of arm 74, and hence hook portion 75, in response to impulses 83 and 84, will have no arresting effect on the ratchet wheel 22, for the reason that the maximum distance that ratchet 22 may be rotated during a character selecting cycle is five steps, which is less than the number of steps between successive pins 76.

Similarly, the restoration impulses 86 received over line wire 315 will pass through magnet 49 and said second winding of magnet 55. The effect of staggering impulses 85 and 86 is to main-

tain lever 74 steadily in its clockwise position, thus giving the effect of a continuous current on the second winding of magnet 55. The reception of the restoration impulses 86 by magnet 49 will cause lever 47 and pawl 46 to rotate ratchet wheel 28 step by step in a counterclockwise direction. As previously described, lever 47 is provided with a vertically extending arm 77 having a laterally extending portion 78. Thus, as lever 47 is oscillated, the portion 78 is reciprocated vertically. Portion 78 is thus free to reciprocate vertically until the segment 34 is presented in its path, whereupon oscillation of lever 47 is prevented. In this manner, type wheel 17, during the restoration operation, can be moved in six-step or six-character-space intervals until segment 34 is presented beneath the portion 78, after which the remaining restoration impulses, if any, will have no effect upon lever 47. The mechanism is so designed that when a pin 76 is intercepted by hook portion 75, and the portion 78 is intercepted simultaneously therewith by segment 34, the type wheel 17 will have reached its zero or starting position with the blank portion on the periphery of the type wheel presented to the printing point.

Segment 34, as previously described, is yieldably connected to shaft 16 by means of coil spring 32. The purpose of this is to prevent segment 34 during the character selection operation, from binding against the lateral portion 78; that is, assuming that segment 34 during character selection is presented with its forward edge 101 just to the right of the vertical path of portion 78, the lever 47 in response to a selecting impulse will be actuated in a clockwise manner, thus bringing portion 78 downwardly into the path of edge 101. Then on its upward movement, lever 47 will actuate ratchet wheel 28 to cause its counterclockwise rotation. However, before ratchet wheel 28 has advanced very far, edge 101 will impinge against portion 78 which has not yet escaped the segment 34. Without the yieldable spring connection between segment 34 and shaft 16, the pressure of pawl 46 against ratchet wheel 28 by means of spring 54 would cause segment 34 to bind against portion 78, thus possibly injuring the mechanism. To compensate for this, segment 34 is permitted to yield and pawl 46 is permitted to complete its action upon ratchet wheel 28, whereafter when portion 78 clears the segment 34, segment 34 will be biased by spring 32 to its normal counterclockwise position.

First modification

In Fig. 5 is shown a modified form of the invention wherein the main features of difference from the preferred form are the substitution for a printing magnet having two windings, of a printing magnet having a single winding of marginal character, and a blocking magnet comparable in effect to the second mentioned winding of the magnet 55 shown in Fig. 2. Furthermore, instead of having pins mounted on the ratchet wheel which controls the single character space movement of the type wheel, a star wheel is provided to cooperate with a blocking arm controlled by the blocking magnet.

The printer shown in Fig. 5 comprises a base plate 102 upon which is supported, in a manner similar to that shown in Fig. 1, a mounting plate 103. Journaled in the mounting plate 103 is one end of a shaft 104, the other end of which is journaled in a bracket (not shown) but similar to bracket 15 of Fig. 2. Carried on shaft 104,

in a manner similar to that shown in Fig. 3, are a type wheel and a pinion (not shown but comparable to type wheel 17 and pinion 21 in Fig. 3), a ratchet wheel 105, and a segment 106. Ratchet wheel 105 is provided with a sleeve portion on which is carried a ratchet wheel 107 comparable to ratchet wheel 28 of Fig. 3.

Ratchet wheel 105 carries a pair of planetary gears, only one gear 108 of which is shown in Fig. 5. Gear 108 meshes with a gear 109 comparable to pinion gear 21 shown in Fig. 3. Ratchet wheel 107 has associated integrally therewith a gear comparable to gear 26 of Fig. 3, which meshes with a planetary gear (not shown) companion to planetary gear 108.

Cooperating with ratchet wheel 105 is a pawl 111 pivotally carried on the end of a pawl operating lever 112. Pawl 111 is normally held into engagement with ratchet wheel 105 by a compression spring 113. Lever 112 is carried by the armature 114 of an electromagnet 115, which is supported on a bracket 116 carried on the mounting plate 103. Armature 114 is pivoted at 117 to bracket 116. Lever 112 is biased in a clockwise direction by a spring 118 and is guided in its oscillatory path by a guide 120.

Ratchet wheel 107 cooperates with a pawl 119 pivotally carried on the end of a pawl operating lever 121. Pawl 119 is biased into engagement with ratchet wheel 107 by a spring 122. Lever 121 is carried by the armature 123 of an electromagnet 124 which in turn is supported on a bracket 125 fixed to the mounting plate 103. Armature 123 is pivotally mounted at 126 to bracket 125. Lever 121 is biased in a counterclockwise direction by a spring 127 and is guided in its oscillatory path by a bracket 128. Lever 121 is also provided with a vertically extending arm 129 which terminates in a laterally disposed portion 131 adapted to cooperate with the segment 106. Carried on a bracket 132 fixed to the mounting plate 103 is a printing magnet 133, the armature 134 of which is pivoted at 135 to bracket 132. A printing lever 136 is fixed to the armature 134 and is biased in its clockwise direction by a spring 137. Lever 136 carries at its right end an upstanding lever 138 which controls a printing platen not shown. Lever 136 also carries adjacent its right end a spacing pawl 139 which is maintained by a spring 141 against a spacing ratchet wheel 142 carried on a shaft 143 journaled in the mounting plate 103. Shaft 143 carries at its opposite end (on the reverse side of plate 103) a friction roller (not shown) comparable to roller 89 in Fig. 1 which cooperates with a pressure roller to effect the spacing movement of the tape. Spacing ratchet 142 is also provided with a spring biased detent 144.

Ratchet wheel 105 instead of being provided with stop pins, similar to pins 76 shown in Fig. 2, has fixedly related thereto a star wheel 145 which cooperates with a blocking arm 146 fixed to the armature 147 of a blocking magnet 148. Armature 147 is pivoted at 149 to a bracket 151 which also carries the magnet 148 and is mounted on the base plate 102. A spring 152 biases the armature 147 and blocking lever 146 in a counterclockwise direction to hold the laterally disposed end 153 of lever 146 normally out of engagement with star wheel 145. As set forth hereinbefore, printing magnet 133 and blocking magnet 148 of the form of invention shown in Fig. 5 are comparable in function to magnet 55 shown in Fig. 2 in that the latter magnet com-

bines the printing winding and the blocking winding, whereas in Fig. 5 these windings are embodied in separate magnets.

In operation, the form of the invention shown in Fig. 5 is substantially the same as that shown in Figs. 1 to 3. Upon receipt of character impulses 83 over the first line wire, magnet 115 connected therein becomes energized intermittently in response thereto to effect the oscillation of lever 112 which, through pawl 111, causes the rotation of ratchet wheel 105 in a clockwise direction a number of angular steps (one for each tooth) equivalent to the number of character impulses received on said first line wire. This counterclockwise movement of ratchet 105 causes through planetary gear 108 the counterclockwise movement of gear 109 because pawl 119 is holding ratchet wheel 107 against movement. This counterclockwise movement of gear 109 is transferred to shaft 105 to cause the movement of the type wheel one character space.

Likewise, the reception of character impulses 84 over the second line wire energizes magnet 124, connected therein, intermittently to impart oscillatory movement to lever 121 which, through pawl 119, rotates ratchet wheel 107 in a counterclockwise direction one tooth distance for each impulse received over the second line wire. This movement of ratchet wheel 107 is imparted to shaft 104, in a manner similar to that shown and described in connection with the preferred form of the invention embodied in Figs. 1 to 3, to cause the type wheel to be rotated through six character spaces for each unit of movement of ratchet wheel 107.

After the reception of the character impulses over the first and/or second line wires, a prolonged printing impulse 81 is received over both line wires, as indicated in Fig. 4, to effect the energization of printing magnet 133. Of course, blocking magnet will at this time be energized to pull up its armature 147 but with no effect, since the type wheel and other mechanism on shaft 104 are at this time quiescent. Thereafter a series of restoration impulses 85 and 86 are received over both line wires concurrently but in a staggered manner, as indicated in Fig. 4, the effect of which is to operate magnets 115 and 124 alternately and to energize the blocking magnet 148 continuously. Due to the marginal character of printing magnet 133 it will not become energized by the restoration impulses since it requires a stronger current than that carried by the restoration impulses to effect its energization.

As magnet 115 operates, it effects, through lever 112 and pawl 111, the counterclockwise rotation of ratchet wheel 105 and star wheel 145. Since blocking magnet 148 is now energized, arm 146 will present its end 153 into the path of star wheel 145, thus permitting star wheel 145 to be rotated until one of its arms impinges against end 153, the remaining restoration impulses on the first line wire, if any, having no effect on the ratchet wheel 105. Similarly, the restoration impulses received over the second line wire will operate the magnet 124 to rotate ratchet wheel 107 (and hence shaft 104 and segment 106) until segment 106 is presented beneath portion 131 of arm 129, whereafter further oscillation of lever 121 is prevented. In this condition, the type wheel is brought to its starting or zero position with the segment 106 just clear of the portion 131. This latter condition is attained due to the fact that after the last restoration impulse 75

has been received and discharged, the magnets 115, 123, and 148 become deenergized and springs 118 and 127 are effective to return their respective levers 112 and 121 to their spring biased positions, thus bringing segment 106 clear of the portion 131 in readiness for a subsequent selection.

Second modification

10 The form of the invention shown in Figs. 6 and 7 is substantially the same as the form shown in Fig. 5 with the exception that the restoration of the type wheel to its zero or starting position is effected mechanically instead of electromagnetically through the instrumentality of restoration impulses; that is, with this form of the invention, the signals received over each line wire are the same as shown in Fig. 4 with the elimination of portion 82 comprising the restoration impulses. 15 In this form of printer the star wheel 145, segment 106, extension 129, blocking lever 146, and magnet 148 of Fig. 5 are eliminated and in their stead a clutch mechanism, generally indicated 154 in Fig. 7, is substituted. Having reference to Fig. 6, shaft 155 is comparable to shaft 104 in Fig. 5; ratchet wheel 156 is comparable to ratchet wheel 105; and ratchet wheel 157 is comparable to ratchet wheel 107. Associated with ratchet wheel 156 is a pawl operating lever 158 comparable to lever 112, and associated with ratchet wheel 157 is a pawl operating lever 159 comparable to lever 121. Also, a printing lever 161 is provided which is comparable to lever 136 in Fig. 5. Now, upon receipt of the signal impulses 83 and 84 the magnets (not shown) controlling the levers 158 and 159 are energized alternately to effect the positionment of the type wheel for character printing, after which the prolonged printing impulse is received over each line 20 wire simultaneously to operate a printing magnet (not shown) comparable to magnet 133 in Fig. 5.

The printing magnet of the printer shown in Figs. 6 and 7, in addition to effecting the printing operation, acts upon the aforementioned clutch mechanism 154 to permit the restoration of the type wheel to its zero or starting position after printing. The driving portion 162 of the clutch has a slideable connection with gear 163, which 25 gear is comparable to gear 109 of Fig. 5. Driving portion 162 is normally urged into meshing engagement with driven portion 164 by a compression spring 165, so that, as the gear 163 rotates, it will impart similar rotation to the driven portion 164. The driven portion 164 is integral with a sleeve 166 which is fixed to the shaft 155. Integral with sleeve 166 is a spiral pulley 167 and a stop arm 168; thus, as gear 163 rotates in response to the character positioning operation of the type wheel, it imparts through the clutch portion 162 like rotation, through the driven portion 164, to sleeve 166. As the type wheel is being rotated during the character selecting operation, the arm 168 and pulley 167 will 30 be rotated in a counterclockwise manner, the pulley as it rotates tending to stretch a return spring 169 which is connected to said pulley by a cord 171, which is directed around an idler pulley 172.

35 After the type wheel has been positioned in response to the selecting impulses, and the prolonged printing impulse has been received to actuate the printing magnet, the printing lever 161 will be actuated in an upward direction as viewed in Figs. 6 and 7 against the action of a

spring 173 to effect, through link 174 and platen member 175, the printing operation. Substantially simultaneously therewith, the printing lever 161 acts through an extension 176 thereon to rotate a bell crank lever 177 (pivotally mounted at 178 to a bracket 179 supported on base plate 102) in a counterclockwise direction (as viewed in Fig. 7). Bell crank 177 acts upon a depending arm 181 of a clutch release lever 182 to rotate said lever 182 in a clockwise direction about its pivot shaft 183 to cause arm 184 of said lever 182 to disengage the driving portion 162 of clutch mechanism 154 from the driven portion 164. Due to the fact that a stabber portion 180 on platen member 175 cooperates with a star wheel (not shown, but comparable to star wheel 18 in Fig. 1) during the printing operation, the sleeve 166 is not, at this time, free to rotate under the pull of spring 169. However, after printing is completed, stabber 180 is withdrawn from the star wheel and sleeve 166 is free to be rotated under the action of spring 169 in a clockwise direction until stop arm 168 strikes against a fixed stop 185.

40 To insure the disengagement of portions 162 and 164 of clutch mechanism 154 for a sufficient period of time to enable the complete return of stop arm 168 to the stop 185, a latch member 186 is provided which cooperates with a vertical arm 187 on clutch release lever 182. Thus, when the clutch release lever 182 is actuated in a clockwise direction to effect the disengagement of portion 162 from 45 164, arm 187 is also actuated in a clockwise direction so as to become latched by the stepped portion of latch 186, due to the action of spring 188. Then just before stop arm 168 reaches its stop 185, it strikes a projection 189 on latch 186 to rotate latch 186 slightly in a clockwise direction against the action of its 50 spring 188 to release said latch 186 from arm 187, thereby permitting compression spring 165 to effect the reengagement of clutch portions 162 and 164.

Third modification

55 In Figs. 8 to 12 inclusive is illustrated a form of the invention embodying rotary-armature type magnets to effect the character positioning of the type wheel. According to this form of the invention, rotary-armature type magnets are substituted for the neutral magnets of the previously described forms of the invention. The printer of the form shown in Figs. 8 to 11 comprises a base plate 201 from which portions 202 (in the present instance two in number) have been struck to provide securing means for a vertical plate 203 (Figs. 9 and 10). Plate 203 provides a support for a short shaft 204 which rests in a bushing 205 held in plate 203 by a nut 206. The right-hand end of shaft 204 (as viewed in Fig. 9) is counterbored to receive the reduced end of a second shaft 207 coaxially aligned therewith. This interconnection between shafts 204 and 207 provides additional support for shaft 204. Shaft 207 is supported, in a manner presently described, in plates 208 and 209 mounted on the base plate 201.

60 Fixed to shaft 204 is a type wheel 211, a star wheel 212, and a sleeve member 213 having a formed integrally thereon a spur gear 214 and a cam portion 215. Meshed with gear 214 is a planetary gear 216 fixed to a stub shaft 217 loosely journaled at the extremity of an arm 218 fixed to the shaft 207. Also fixed to the stub shaft 75

217 is a companion planetary gear 219 which meshes with a pinion gear 221 pinned to a sleeve member 222. Sleeve member 222 is loosely mounted on shaft 207 and carries fixedly thereon 5 a rotary-armature 223, Figs. 8 and 9. Integral with sleeve 222 is a multiple-toothed cam member 224 having cam teeth equal in number to the number of poles on the rotary-armature 223. Cooperating with cam member 224 (as viewed in 10 Fig. 8) is a follower roller 225 carried at the extremity of a lever 226 pivoted at 227 to the mounting plate 208. Lever 226 is biased in a counterclockwise direction to hold roller 225 against cam 224 by a spring 228. The cam teeth 15 on the multi-toothed cam 224 are so conformed or shaped as to assist the rotary-armature magnet 229 in rotating the armature 223 in a manner to be presently described.

Armature 223 is rotatable between arcuate core 20 pole faces 286, the curvature of which is generated on a constant radius from the axis of rotation of armature 223 as a center. Pole faces 285 of armature 223 are curved in conformity with a 25 spiral generated from the axis of rotation of armature 223 by uniform increase in radii between the leading and trailing edges of a pole face 285. It may be added that the spirally conformed surfaces of all of the pole faces 285 are identical, the radii at the leading edges of all being equal, the 30 radii at the trailing edges of all being equal, and the variation in radii from maximum to minimum being uniform for all of the pole faces. Thus, the leading edges of all the armature pole 35 faces pass the core pole faces 286 at a predetermined distance 289 therefrom so as to provide a gap therebetween, and the trailing edges pass the core pole faces at a lesser distance 291 therefrom, so that the gap is continuously diminished 40 as an armature pole face passes into and out of range with a core pole face 286. The armature 223 is revolved by means of the attraction exerted by the poles 231 and 232 of magnet 229. The curvature of faces 285 is such that as the armature-poles advance within the field of the magnet 45 poles 231 and 232, the separation of the arcuate faces 285 from the pole faces 286 diminishes. The position of strongest attraction, therefore, is opposite those portions of edges 285 last to reach 50 the pole faces 286, and the armature 223 tends to stop in such position. Thus, upon energization of magnet 229, a magnetic path will be set up between poles 231 and 232 such that the rotary-armature will be rotated initially (in a clockwise 55 direction as viewed in Fig. 8) an amount sufficient to raise the follower roller 225 to the high point on the tooth of the multi-toothed cam 224, after which spring 228 acts through lever 226 and follower roller 225 to urge the cam 224 and rotary-armature 223 an additional angular amount.

Accordingly, armature 223 is revolved by means of the alternate action thereon by poles 231—232, and cam means 224, 225, 226, 228.

Also carried on sleeve 222 is an arm 233 (Figs. 60 9 and 11) which is fixedly carried upon sleeve 222 by being clamped against the rotary-armature 223 by a nut 234. The function of arm 233 in the restoration operation will presently appear. Fixed to the shaft 207 is a sleeve 235 which is 65 provided integral therewith with a multi-toothed cam 236. A rotary-armature 237 is carried on sleeve 235 as is also a star wheel 238, both of which are fixed to the sleeve 235 by the clamping action of a nut 239. As previously indicated, shaft 207 is journaled in the bracket 209 and

to afford a broader bearing at this point, a ring portion 241 is provided which is secured to the bracket 209.

The rotary-armature 237 is associated with the poles 242 and 243 of electromagnet 244. A 5 detent roller (not shown) is also provided to cooperate with the multi-toothed cam 236 in the same manner that follower roller 225 cooperates with cam 224. The action of electromagnet 244 upon its armature 237 in response to each energizing impulse is the same as previously described in connection with magnet 229 and armature 223.

Stop arm 233 cooperates with an extension 245 (Fig. 11) integral with an armature member 246 pivoted at 247 to a bracket 248. The armature 246 is so designed as to span pole faces 231 and 242 so that it acts in response to both magnets 229 and 244. Armature 246 is biased to its counter-clockwise position against an adjustable stop 249 by a spring 251. Star wheel 238 co- 20 operates with a stop lever 252 which is fixed to a rock shaft 253 mounted in brackets 248 and 238. Fixed to the opposite end of shaft 253 (as viewed in Fig. 8) is a cam follower arm 254 which is biased in a counterclockwise direction 25 against the cam 215 by a spring 255. A detent spring 256 (Fig. 11) cooperates with armature 237 to prevent back slip. A similar spring (not shown) is also provided for armature 223.

As shown in Fig. 10, there is mounted on base 30 plate 201 an electromagnet 257 which controls the printing operation and which is also provided with a rotary-armature 258 similar in design to armature 237. Armature 258 is fixed to a sleeve 259, which in turn is pinned to a shaft 261 journaled in the bracket 208, and also in a bracket 262 mounted on base plate 201. Fixed to shaft 261 is a sleeve member 263 which has integral therewith a gear portion 264 and a multi-toothed cam portion 265. Gear 264 meshes with a gear 40 266 (Fig. 8) mounted on a stub shaft 267 carried in plate 203. Shaft 267 controls the character spacing of the tape by being provided with a spacing roller (not shown) in a manner similar to roller 89 in Fig. 1.

Cam 265 cooperates with a follower roller 268 carried at one end of a lever 269 fixed to a short shaft 271. Lever 269 is biased in a counterclockwise direction (as viewed in Fig. 8) by a spring 272 to hold follower roller 268 against 50 cam 265. Shaft 271 is suitably supported in a bearing 273 (Fig. 10) carried in plate 203 and has fixed to its outer end a printing arm 274 which cooperates with a platen 275 pivoted at 276.

Mounted above arm 226 (Fig. 8) is a contact assembly 277, in which contact 278 is normally closed and contact 279 is normally opened. Lever 226 acts through insulated stud 281 to control the contact assembly 277.

In Fig. 12 is shown diagrammatically the electrical circuit for operating the magnets 229, 244, and 257. Magnet 229 is connected to line wire 282 which will hereinafter be designated as the first line wire. The second line wire 283 is connected to terminal 284 (Figs. 8 and 12) of the contact assembly 277 and normally completes a circuit for character selecting impulses over wire 283, terminal 284, contact 278, magnet 243 to ground. The impulses over the first line wire are 70 directed over conductor 282 through magnet 229, thence to ground. The purpose of contact assembly 277 is to disassociate the printing magnet 257 from the line wire 283 during the reception of character selecting and restoration impulses since 75

otherwise magnet 257 would have a tendency to operate prematurely.

Upon reception of the character selecting impulses which are of the nature of impulses 83 and 84 shown in Fig. 4, magnets 229 and 244 will be energized alternately. In response to each selecting impulse over wire 282, magnet 229 will be energized momentarily to cause its rotary-armature 223 to be attracted to cause the surfaces 285 of oppositely disposed arms thereof to register opposite the faces 286 of poles 231 and 232. This magnetic attraction imparts a predetermined amount of rotation to armature 223, which amount is sufficient to cause follower 15 roller 225 to ride up on the high part of a tooth of the cam 224 whereafter, upon deenergization of magnet 229, spring 228 acts to rotate cam 224 a predetermined additional distance to the bottom of the slope of said cam tooth. It is thus seen that the armature 223 is rotated in part by the magnet 229 and in part by the spring 228 cooperating with the multi-toothed cam 224.

This movement imparted to rotary-armature 223 is transmitted through gear 221 to planetary gears 219 and 216 which, through gear 214 and shaft 284, causes the type wheel 211 to rotate a single character step. It is understood that the proportions of the gears 211, 219, 216, and 214, are chosen to properly translate the movement of armature 223 to the type wheel 211. It should be noted that when lever 226 is rocked upwardly by the cam 224, contact 278 will be opened momentarily and the contact 279 will be closed.

35 When a character signal impulse is received over the second line wire 283, it effects the energization of magnet 244 which, when energized, causes armature 237 to rotate until the points of opposite poles register opposite the pole faces 242 and 243, the action being the same as described in connection with armature 223. During this initial rotation, the cam follower roller (not shown) associated with cam 236 will ride onto the high part of a cam tooth preparatory to imparting additional rotation to said cam at the termination of the signal impulse. In this manner, shaft 287 is rotated to impart, through arm 218, movement to planetary gears 219 and 216 and gear 214 to rotate type wheel 211 six character positions. It is thus seen that character selecting impulses which are received over line wires 282 and 283 in varying combinations result in the corresponding rotation of type wheel 211 to effect the proper position thereof in accordance with the character selected.

55 After the character impulses 82 and 83 have been received, a prolonged printing impulse 81 is received simultaneously over wires 282 and 283. The effect of the printing impulse on magnet 229 will be to hold the rotary-armature opposite the pole faces 286, thereby maintaining the follower roller 225 at the apex of a tooth on the multi-toothed cam 224. In this position the contacts 279 are closed and the contacts 278 60 opened so that the printing impulse received over wire 283 (which is slightly retarded to insure the prior closing of contact 279) is transmitted through terminal 284 and contacts 279 through printing magnet 257 to ground. The effect of 65 this energization of magnet 257 will be to rotate the rotary-armature 258 initially to cause follower roller 268 to ride onto the apex of a tooth on the multi-toothed cam 265. This action of cam 265 upon follower roller 268 causes lever 70 75 269 to rotate in a clockwise direction about pivot

shaft 271, which rotation is imparted through shaft 271 to printing arm 274 and thence to the platen 275, thereby throwing the platen 275 against the type wheel 211 to effect printing of the selected character. Lever arm 274 is provided with a knife-edge 287 which during the printing operation cooperates with the star wheel 212 to hold the type wheel 211 fixed during the printing function.

Following the receipt of the printing impulse, 10 the restoration impulses 85 and 86 are received, and their action upon the restoration mechanism is similar in principle to that described in the previous forms of the invention. Since the restoration impulses are received alternately over 15 line wires 282 and 283, the alternate energizations of magnets 229 and 244 cause substantially continuous attraction of common armature 246 to bring extension 245 into the path of stop arm 233. Stop arm 233 being controlled by the one- 20 step armature 223 will be rotated until it is arrested by extension 245.

The restoration impulses received over line 25 wire 283 will energize the six-step magnet 244 to cause rotation of the type wheel 211 in the manner previously described. However, when the high part of cam 215 cooperates with a follower arm 254, stop arm 252 will be rotated into the path of the arms of star wheel 238 so that after this occurs, further restoration impulses 30 will be ineffective to rotate armature 237. When this condition exists whereby stop arm 233 is arrested by extension 245 and star wheel 238 is arrested by lever 252, the type wheel is so positioned that the initial or starting position is 35 one-step or character space removed from the actual zero point, so that upon deenergization of magnets 229 and 244, stop arms 245 and 252 will be removed from their stopping position thus permitting the follower rollers to act upon their respective cams 224 and 236 to impart final rotation to type wheel 211, thus bringing type wheel 211 into its actual starting or zero position.

Transmitting mechanism

45 In Figs. 13 to 19 inclusive are shown various forms of transmitters and circuits therefor which may be employed in connection with the receiving printers according to the invention. In Figs. 13 to 15 inclusive is illustrated a keyboard transmitter of the type shown and disclosed in United States Patent No. 1,595,472. As shown in Figs. 13 and 14 the keyboard portion, indicated generally as 301, is provided with a set of keys 302 arranged similarly to the well-known typewriter keyboard, and, as illustrated in Fig. 13, key levers 303 associated with the keys 302 are pivotally mounted on a common shaft 304 and are spring held in normal horizontal position by individual springs (not shown). Arranged transversely below the key levers 303 (Fig. 14), in operative relation thereto, are a series of V-notched selector bars 305 which are adapted to be operated permutably, in well-known manner, in accordance with the key depressed.

50 The selector bars 305 are pivotally articulated to a corresponding series of locking latches 306 which are adapted to be rocked to either of two positions thereby. Associated with latches 306 is 55 a corresponding series of contact levers 307 for making and breaking contacts 308. Contact levers 307 cooperate with individual contact cams 309 mounted on shaft 311. The shaft 311 is provided with a single revolution clutch mechanism 60 65 70 75 75

(not shown) which is controlled by a universal bar member as set forth in Patent No. 1,595,472. The operation of the transmitting unit consists essentially in the depression of a key lever 5 303 which effects the arrangement of the set of selector bars 305 periodically in accordance with a predetermined code combination, the setting of which determines the position of the locking latches 306. The rotation of the cams 309 is 10 initiated substantially simultaneously with the setting of the locking latches 306, and a locking loop 312 controlled by a cam 313 is permitted to rotate in a counterclockwise direction (Fig. 14) to effect the locking of latches 306. The 15 setting of the locking latches 306 determines whether the contact levers 307 shall or shall not be affected by their associated cams 309 to cause the opening or closing of their associated contacts 308 to transmit over a signal line (as will 20 appear presently from a description of Fig. 16) to the receiving station a predetermined combination of signalling impulses. The respective notches in the cams 309 are arranged in a spiral progression so that upon the rotation of the cam 25 assembly, the contacts 308 will be controlled successively.

In the present form of transmitter, the contact cams 309 are eight in number and are divided in groups of four each, each group of four 30 being connected to a separate line wire over a two wire telegraph system. In Fig. 15 is shown the series of eight contact cams 309 with their respective contact levers and contacts. In this 35 illustration, contact cams 321, 322, 323, and 324 comprise one group, the contacts 308 of which are connected over line wire 314 of Fig. 16, and contact cams 331, 332, 333, and 334 comprise a second group, the contacts 308 of which are connected over a second line wire 315 of Fig. 16. 40 It will be noted that contact cams 321 and 331 are provided with a single depression in response to which a single impulse is transmitted through a contact 308 for each revolution of the cam. It will be noted further that cams 322 and 323 45 and cams 332 and 333 are each provided with two adjacent notches so that for each revolution of these cams, two impulses will be transmitted. Then to enable the sending of one to five character impulses over each wire 314 and 315, the 50 cams in each group may be selected in proper combinations; for example, to send a single impulse over line 314, cam 321 only would be operated. To transmit two impulses over line 314, cam 322 or cam 323 will be operated. To send three impulses over line 314, cam 321 would be 55 operated simultaneously with cam 322 or 323. To send four impulses over line 314, cams 322 and 323 would be operated simultaneously, and to transmit five signals over the line all of the 60 cams 321, 322, and 323 would be operated simultaneously. The same permutable operation of the second group of cams 331, 332, and 333 is effected to transmit signals over line 315. It will 65 be observed that the notches of each group of cams are arranged in a progressive manner.

Cams 324 and 334 are not controlled by lock latches 306 and are permitted to rotate invariably for every operation of transmitting shaft 311. Each of the cams 324 and 334 is so cut as to transmit (following the character selecting impulses) 70 first the prolonged printing impulse and thereafter six restoration impulses.

Having reference to Fig. 16 there is shown a circuit diagram for a two wire telegraph system employing the transmitter shown in Figs. 13 to 15

and printers according to Figs. 1 to 4, for example, herein described. According to this system, impulses in accordance with the diagram shown in Fig. 4 are transmitted from battery 335, through contacts 308, over line wires 314 and 315, 5 through their respective stepping magnets 38 and 49, thence through printing magnet 55 to ground.

In Figs. 17 to 19 is shown a dial type of transmitter. In accordance with this form of transmitter, a series of dialing keys 351 are disposed above a casing 352, and integral with each dialing key is a key lever 353 loosely carried upon a shaft 354. Each of the key levers 353 is provided with oppositely directed arcuately shaped arms 355 and 356, the upper arcuate edges of which are notched 15 in code manner. Associated with the arm 355 of each of the key levers 353 is a pin 357 carried on a common rod 358 suitably journaled in the casing 352. There is also carried on the rod 358 a contact operating pin 359 which cooperates with the 20 upper blade 361 of contact 362. The assembly comprising rod 358 and pins 357 and 359 are biased in their clockwise direction (as viewed in Fig. 17) by a spring 363. When a key lever 353 is rotated in a counterclockwise direction, the 25 code projections on the arm 355 rock the rod 358 repeatedly in a clockwise direction and rotate arm 359 away from the contact 362. Then, upon the return of key lever 353 to its rightward or clockwise position (as shown in Fig. 17) the code projections on arm 355 will again rock rod 358 repeatedly in a counterclockwise direction against the action of spring 363 to close the contact 362 intermittently to transmit impulses over the line 30 wire, as will be hereinafter explained. 35

Similarly there is associated with the arm 356 of each of the key levers 353 a pin 364 which is carried upon a common rod 365. There is also fixed to rod 365 a contact operating pin 366 which operates a contact 367. As a key lever is rotated counter-clockwise, the code projections upon arm 356 act, through pins 364, to rock rod 365 repeatedly in a clockwise direction and rotate arm 366 away from contact 367. Then, upon return of the key lever 363 to its clockwise position, the 40 code notches on arm 356 act to rock rod 365 repeatedly in a counterclockwise direction against the action of its spring 368 to close contact 367 intermittently to transmit signal impulses over 45 a second line wire. 50

According to the presently described form of the invention, means is provided for preventing the operation of more than one key lever 353 at a time; that is, when one key lever 353 is operated, all of the remaining key levers are locked 55 against operation. To achieve this result, an arm 369 is associated with each key lever which arms 369 are fixed to the shaft 354. Pivotedly carried on key lever 363 adjacent the outer extremity of arm 369 is a bell crank lever 371. There is also 60 carried on key lever 363 a bell crank lever 372, and bell cranks 371 and 372 are biased attrahently by a common spring 373. Extending longitudinally through the casing 352 and supported therein is a rod 374 which cooperates with bell 65 cranks 371 and 372. Also fixed to the shaft 354 is an arm 375 to the extremity of which is connected one end of a spring 376, the other of which is anchored to the casing 352. Thus, in this manner, all of the arms 369 are biased to their clockwise position against a stop 377 carried on each 70 of the key levers 353.

When the arms 369 assume their clockwise position against stops 377, their ends 378 thereof also bear against bell cranks 372 to rotate the lat- 75

ter sufficiently to remain disengaged from bar 374 as indicated in Fig. 17. Also when key lever 363 is held in its clockwise position, bell crank lever 371 bears against bar 374 in such a manner as to 5 maintain its horizontal arm disengaged from end 378 of arm 369.

Now, when a key lever 353 is operated by means of its associated dialing key 351, and is thereupon actuated in a counterclockwise direction, its pin 10 377 engages arm 369 and carries said arm forwardly therewith. This action is rendered possible because arm 369 is still bearing against bell crank 372 to hold said bell crank disengaged from bar 374, and as lever 353 is moved counterclockwise, bell crank 372 passes under the bar 374. Since all of the arms 369 are fixed to shaft 354, the remaining arms 369 will be moved independently of their associated key levers 353. Then, 15 because of this operation of arm 369 independently of key levers 353, bell cranks 372 of all but the operated key lever 353 will be free to be actuated by their respective springs 373, so as to bring the horizontal arms of bell cranks 372 into latching engagement with bar 374. Therefore, so long 20 as arms 369 of all but the operated key lever 353 remain out of contact with their respective bell cranks 372, all of the remaining key levers 353 are locked against operation. In Fig. 18 is shown 25 a plan view of the dial transmitter with a part 30 broken away to show the contact 362.

In Fig. 19 is shown a circuit diagram of a two wire telegraph system employing the dial transmitter shown in Figs. 17 and 18. In this system the contact 362 is operated intermittently 35 in accordance with the code notches on the arm 355 of a key lever 353 to transmit impulses over the first line wire 379 through a stepping magnet 381 and print magnet 382 to ground. Similarly, contact 361 is operated intermittently 40 in response to the code notches on the arm 356 of a key lever 353 to transmit over a second line wire 383 signal impulses to a stepping magnet 384 thence through the print magnet 382 to ground. Since print magnet 382 is of marginal operation, it will not respond to impulses received over either line wire singly but only when 45 a printing impulse is received over both line wires 379 and 383 simultaneously. It is understood that the code notches on arms 355 and 356 may 50 comprise the character signaling impulses, the printing impulse, and restoration impulses in accordance with the signal indicated in Fig. 4, or in the event that a printer such as shown in Figs. 6 and 7 is employed, the restoration impulses will 55 be omitted; the restoration of the type wheel being effected, it will be recalled, in response to the printing impulse, by a spring return means.

Although the present invention has been disclosed in connection with certain specific embodiments thereof, it is understood that such embodiments are merely illustrative and not restrictive, and that all forms coming within the scope of equivalency of the appended claims are intended 60 to be covered by the invention.

65 What is claimed is:

1. In a printing telegraph receiver, a dually controlled type wheel, electromagnetic means responsive to signal impulses for controlling the movement of said type wheel, and planetary gearing interposed between said type wheel and said means for effectuating said control. 70

2. In a printing telegraph receiver, a dually controlled type wheel, combination rotary-armature and mechanical means responsive to signal impulses for controlling the movement of said 75

type wheel, and planetary gearing interposed between said type wheel and said combination means for effectuating said control.

3. In a printing telegraph receiver, a dually controlled type wheel, unidirectional rotary-armature means responsive to signal impulses to initiate each step-by-step movement of said type wheel, and spring and cam means effective supplementally to consummate each said movement.

4. In combination in a printing telegraph receiver, a dually controlled type wheel, a first rotary-armature means responsive to signal impulses for controlling the movement of said type wheel in one manner, a second rotary-armature means responsive to signal impulses for controlling the movement of said type wheel in another manner, a third rotary-armature means for controlling the printing of the selected character, and means effective only when said first and second means are operated simultaneously to render said third means effective.

5. In a telegraph system, two channels of transmission, a transmitting means comprising two groups of transmitting elements, one group 25 for each channel, means whereby said elements are operative to impress initially character selecting impulses over each channel in staggered manner and to impress subsequently printing impulses coincidentally over said channels, and 30 receiving apparatus comprising character selecting means in each channel responsive to said staggered impulses, and a recording means common to both channels responsive to said coincidental printing impulses to effect printing of 35 the selected character.

6. In a telegraph system, two channels of transmission, a transmitting means comprising two groups of transmitting elements, one group 40 for each channel, means whereby said elements are operative in a single cycle to impress initially character selecting impulses over each channel in staggered manner, followed by a printing impulse occurring coincidentally on each channel, and receiving apparatus comprising a dually 45 controlled character carrying means, a first electromagnetic means responsive to the character selecting impulses over one of said channels for controlling the movement of said character carrying means in one manner, a second electromagnetic 50 means responsive to the character selecting impulses over the other of said channels for controlling the movement of said character carrying means in another manner, and a third electromagnetic means common to both channels 55 responsive to said coincidental printing impulses for controlling the printing of the selected character.

7. In a recorder, a dually controlled recording means, means responsive to signal impulses for controlling the operation of said recording means, and planetary gearing interposed between said recording means and said controlling means for effectuating said control.

8. In a recorder, a dually controlled recording means, electromagnetic means responsive to signal impulses for controlling the operation of said recording means, and planetary gearing interposed between said recording means and said electromagnetic means for effectuating said control. 70

9. In a recorder, a dually controlled recording means, combination rotary-armature and mechanical means responsive to signal impulses for controlling the movement of said recording 75

- means, and planetary gearing interposed between said recording means and said combination means for effectuating said control.
10. In a recorder, a dually controlled recording means, unidirectional rotary-armature means responsive to signal impulses to initiate each step-by-step movement of said recording means, and spring and cam means effective supplementally to consummate each said movement.
11. In combination in a printing telegraph receiver, a dually controlled type wheel, a first electromagnetic means responsive to signal impulses for controlling the movement of said type wheel in one manner, a second electromagnetic means responsive to signal impulses for controlling the movement of said type wheel in another manner, a third electromagnetic means for controlling the printing of the selected character, and means associated with each electromagnetic means cooperating to control the restoration of said type wheel to its zero position prior to each character selection.
12. In combination in a printing telegraph receiver, a dually controlled recording instrumentality, a first means responsive to signal impulses for controlling the movement of said recording instrumentality in one manner, a second means responsive to signal impulses for controlling the movement of said recording instrumentality in another manner, a third means for controlling recording operations, and means associated with each of said first, second, and third means acting conjointly to control the restoration of said recording instrumentality to its zero position prior to each character selection.
13. In a printing telegraph receiver, recording means, means responsive to signal impulses for controlling the movement of said recording means, return means for said recording means, clutch means interconnecting said return means and said recording means, means to operate said recording means to effect recordations, and means actuated by said last recited means to control, through said clutch means, the operation of said return means.
14. In a recorder, recording means, means for controlling the movement of said recording means, spring-return means for said recording means, clutch means associated with said return means and said recording means, means to operate said recording means to effect recordations, and means actuated by said last recited means to control, through said clutch means, the operation of said return means.
15. In a telegraph system, two channels of transmission, a transmitter comprising a series of keys, a permutation code selector mechanism, and two groups of contact controlling cams, one group for each channel, means whereby said cams are controlled permutably by said selector mechanism and operative in a single cycle to impress initially character selecting impulses over each channel in staggered manner, followed invariably by a printing impulse occurring coincidentally on each channel and subsequently a definite series of restoration impulses occurring on each channel in staggered manner, and receiving apparatus comprising character selecting means responsive to said first recited staggered impulses to effect the character selection in variable steps in accordance with the variable number of impulses applied to each signal channel, recording means common to both channels responsive to said coincidental printing impulses to effect printing of the selected character, and restoration means responsive to said restoration impulses to restore said character selecting means to zero position.
16. In a telegraph system, two channels of transmission, a transmitting means comprising two groups of transmitting elements, one group for each channel, means whereby said elements are operated in a single cycle to impress initially character selecting impulses over each channel in staggered manner followed by printing impulses impressed coincidentally over said channels and subsequently restoration impulses impressed over each channel in staggered manner, and receiving apparatus comprising a character carrying instrumentality having a normal position, character selecting means in each channel responsive to said initially impressed character selecting impulses to control said instrumentality, a recording means common to both channels responsive to said coincidental printing impulses to effect printing of the selected character, and restoration means responsive to said restoration impulses to return said instrumentality to its normal position.
